UNITED STATES PATENT OFFICE

JULES W. DROZ, JR., OF SALT LAKE CITY, UTAH

DOOR RETAINER

Application filed May 27, 1929. Serial No. 366,415.

My present invention has reference to a combined door stop and latch and is primarily designed for employment in connection with garage or like doors.

5 A further object is the provision of a device for this purpose in the nature of a right-
angular stake to be partially driven into the
ground and to have one of its flanges con-
tacted by the door when the latter is swung
10 to open position, while the second flange has
swingably and adjustably secured thereon a
catch member to engage with the door and
hold the same in its said open position.

To the attainment of the foregoing and
15 other objects which will present themselves,
the improvement also resides in certain other
novel features of construction, combination
and operative association of parts, one satis-
factory embodiment of which is disclosed by
20 the accompanying drawings.

A further object of the invention is to
provide an extremely simple and reliable
door retainer, which may be constructed of
a few parts that may be made at a minimum
25 cost, and operated by the foot, thus eliminat-
ing the necessity of stooping down.

In the drawings:

Figure 1 is a plan view of a garage, with
parts in section, and showing the doors there-
30 for swung and held in open position in ac-
cordance with this invention.

Figure 2 is a detail elevation of the im-
provement with the latch engaging the door
and the stake being driven in the ground,
35 which latter is shown in section.

Figure 3 is a side elevation of the stake
looking at the side thereof opposite that dis-
closed by Figure 2.

Figure 4 is an enlarged sectional view ap-
40 proximately on the line 4-4 of Figure 3,
looking in the direction of the arrows.

Of course, when the improvement is em-
ployed in connection with two doors as dis-
closed by Figure 1 of the drawings two of
45 my improvements are employed.

The improvement as above stated, is pri-
marily designed as a stop and latching means
for a garage or other outwardly swinging
doors.

50 In the drawings the numeral 1 designates

a hinged and outwardly swinging door. At
a suitable distance away from the garage
upon which the door 2 is hinged I force into
the ground surface the pointed end 3 of the
stake member 4 of the improvement. By 55
reference to the drawings it will be seen that
the stake member is in the nature of a right
angle plate and is preferably of metal or
some other suitable hard material. The
stake member is so positioned that one of the
60 flanges thereof, indicated by the numeral 5
will be contacted by the door while the outer
edge of the door is disposed only a slight dis-
tance away from the second flange 6. At the
top of the said second flange 6 I arrange a 65
plate 7 that has an elongated slot 8 there-
through. A nut engaged by a bolt member
9 is passed through the flange 6 and through
the slot 8. The bolt preferably contacts with
the washer 10. There is hinged, as at 11, on
70 the upper edge of the plate, which is ar-
ranged in a line with or projects slightly
above the upper edge of the flange 6 a swing-
able member in the nature of a latch 12. As
disclosed by the drawings the outer corner of
75 this latch is rounded. When the door is
swung against the flange 5 the latch 12 is
swung to horizontal position so that the same
will engage with the inner face of the door.
The stake 4 provides an abutment for the
80 door and the swingable element 12 provides
a catch for the door for holding the latter
in open position. By arranging the swing-
able catch 12 on the plate 7, which it will be
noted is adjustably secured to the flange 6,
85 the said plate may be adjusted with respect to
the flange 5 so that the latch plate 12 will thus
engage with doors of varying thicknesses.

The simplicity and advantages of my im-
provement will, it is thought, be obvious to
those skilled in the art to which the inven-
tion relates. The device is of an extremely
simple nature and may be conveniently oper-
ated without the necessity of stooping as the
operation of lifting the latch 12 back and
forth can be easily accomplished by foot pres-
sure. A further detailed description is not
believed necessary, although I do not wish
to be restricted to the precise details herein
set forth and, therefore, hold myself entitled 100

to make such changes therefrom as fairly fall within the scope of what I claim.

Having described the invention, I claim:

1. A combined abutment and latch for outwardly swinging doors, comprising a rightangular stake designed to be partly driven into the ground and to have one flange thereof contacted by a door when the latter is swung to open position, and a hinged catch 5 on the upper face of its second flange swingable and designed to rest on the said upper end of the second flange for engaging with the face of the door.
2. A combined abutment and latch for outwardly swinging doors, comprising a right- 15 angular stake designed to be partly driven into the ground and to have one flange thereof contacted by a door when the latter is swung to open position, and a swingable catch on its second flange swingable and designed to rest on the upper end of the second flange for engaging with the face of the door and a laterally adjustable plate on said second flange on which the latch is hinged.
3. A combined abutment and latch for outwardly swinging doors, comprising a right- 20 angular stake designed to be partly driven into the ground and to have one flange thereof contacted by a door when the latter is swung to open position, a hinged catch on the upper end of its second flange, swingable thereover in the direction of and designed to have its inner edge parallel with the door abutting flange, and a laterally adjustable plate on said second flange, binding means 25 for holding the plate adjusted, and said catch being hinged to the upper edge of the adjustable plate.

In testimony whereof I affix my signature.
